FLIGHT CONNECTION FOR CHAINS

Filed Dec. 8, 1945

UNITED STATES PATENT OFFICE

2,467,193

FLIGHT CONNECTION FOR CHAINS

Philip C. De Bruyne, St. Charles, Ill., assignor to
 Moline Malleable Iron Co., St. Charles, Ill., a
 corporation of Illinois

Application December 8, 1945, Serial No. 633,737

4 Claims. (Cl. 198—176)

1

My invention relates to an improvement in conveyors and relates particularly to flights for conveyor chains which may be employed for conveying materials.

Another purpose is to provide a flight which may be readily applied to and removed from a chain.

Another purpose is to provide a flight which itself connects or completes two adjacent chain links or link portions.

Another purpose is to provide connecting means for a flight in which there shall be a minimum of outward projections which can be battered or deformed by use.

Another purpose is to provide improved means for connecting a flight to a chain.

Other purposes will appear from time to time in the course of the specification and claims.

The invention is illustrated more or less diagrammatically in the accompanying drawings wherein:

Figure 1 is a plan view illustrating the flight connected in a chain;

Figure 2 is a plan view on an enlarged scale of the flight structure;

Figure 3 is a section on the line 3—3 of Fig. 2;

Figure 4 is a section on the line 4—4 of Figure 2;

Figure 5 is a section on the line 5—5 of Figure 4;

Figure 6 is a side elevation;

Figure 7 is a section on the line 7—7 of Figure 3, and

Figure 8 is a perspective view of a half link adapted to be secured to the flight.

Like parts are indicated by like symbols throughout the specification and drawings.

Referring to the drawings I illustrate a chain including links 1 which may lie in a horizontal plane and connecting links 2 which may lie in a vertical plane. The flight structure proper is shown as including a bottom or base plate 3 which has its largest width, from front to back, in its middle section, and has forwardly inclined rear edges 4 at each side of the flight. Along its generally rectilinear front edge 5 is an integral upwardly extending front wall 6 shown as further connected to the base plate 3 by end webs or reinforcements 9 and intermediate ribs or reinforcements 10. Upwardly extending from the base plate 3 and formed unitarily with the base plate and with the front wall 6 is a connecting portion generally indicated as 11. It includes upwardly extending side walls 12, 13 which are reinforced at their rear ends by webs or ribs 14

which are unitary with the walls 12, 13 and with the bottom plate 3. The webs 14 are separated by a slot 15 which extends substantially from top to bottom of the structure. A corresponding forward slot 16, preferably of identical size and shape, breaks the forward surface of the front wall 6, the two slots being aligned along the axis of the chain. Intermediate top and bottom reinforcements or transverse connecting portions 17, 18 connect the side walls 12, 13. The side wall 13 is provided with an entry aperture 20 adapted to receive a key 21 which is shown as having flat upper and lower faces and as being substantially wider than its depth. It is provided with an end portion 22 which enters a recess 23 in the wall 12. The recess may extend entirely through the wall but preferably terminates somewhat short of the outer face of the wall, to provide a flush face. The key 21 may be locked in position by the set screw 24 which has a lower portion 25 which enters an appropriate aperture 26 in the end 22 of the key 21 and which, if desired, can be extended downwardly into an aperture 27 in the wall 12. Any suitable tool 28, indicated in dotted line in Fig. 4, may be employed to enter the aperture 29 in the end of the set screw 24. When the set screw is in position it is preferably flush with the top of the wall 12. Similarly, the end of the key 21 is preferably flush with the side surface of the wall 13.

It will be clear from Fig. 2 that the recesses or slots 15, 16 communicate with enlarged portions or cavities 30, 31 which are open topped. Into these may be dropped the ends of half links such as are shown in Fig. 8. Each such half link includes an upper portion 33 and a lower portion 34 connected by a bend 35. At the end of the portions 33 and 34 are lateral enlargements 36, 37, which conform generally to the contour of the open topped cavities 30 and 31. The members 36 and 37 are shown as outwardly tapered cross bars. It will be noted also that the lower link portion 34 defines a link receiving seat or depression 38, as is clear for example from Figs. 6 and 7. The links may be dropped in to position prior to the insertion of the key 21. When the half links are in the position in which they are shown in Figs. 2 and 7 the key 21 may be inserted through the aperture 20 in the wall 13. It will then take the position in which it is shown in Fig. 7 and will lock the half links against upward removal. In order to prevent unintended movement of the key 21 the set screw 24 is then inserted, taking the position in which it is shown in Fig. 4. Thereafter the half links cannot be

removed unless and until the operator unscrews and removes the set screw 24, and removes the key 21. It will be understood, of course, that the half links are connected with adjacent chain links 1, as shown in Fig. 1, before they are inserted into the flight. It will be noted that the key 21 and the set screw 24 have no outwardly extending portions and are substantially flush with the adjacent faces of the walls 12 and 13. Preferably the upper surfaces of the half links are substantially flush with the upper surface of the flight, as shown for example in Fig. 7.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

I claim:

1. In a flight adapted for removable attachment to chains, a flight structure including an integral chain receiving portion having side walls and generally parallel slots extending to the top of the flight, said slots being formed and adapted to receive half links having laterally enlarged end portions, means for holding said half links from unintended upward movement in said slots including a key adapted to interpenetrate with said side walls, one side wall being apertured to permit the insertion of the key therethrough, the other side wall having an internal recess adapted to receive and protect the inner end of said key, and securing means, insertable from outside the flight structure, adapted to penetrate said key.

2. In a flight adapted for removable attachment to chains, a flight structure including an integral chain receiving portion having side walls and generally parallel slots extending to the top of the flight, said slots being formed and adapted to receive half links having laterally enlarged end portions, means for holding said half links from

unintended upward movement in said slots including a key adapted to interpenetrate with said side walls, one side wall being apertured to permit the insertion of the key therethrough, and securing means, insertable from outside the flight structure, adapted to penetrate said key, including a socketed set screw having an outer end flush with the top of one of said side walls.

3. In combination, in a flight structure and chain, a flight having a transversely extending body portion provided with front and rear slots open at the top, half links having end portions adapted to penetrate and be seated in said slots, and means for holding said links against unintended movement in said slots, each said link including an upper and a lower arm connected by a bend, and having an outwardly tapered cross bar at the end of each said arm, said cross bars being of uniform length and taper, said slots being formed to conform generally, in horizontal cross section, to said cross bars.

4. In combination, in a flight structure and chain, a flight having a transversely extending body portion provided with front and rear slots open at the top, half links having laterally enlarged end portions adapted to penetrate and be seated in said slots, and means for holding said links against unintended movement in said slots, each said link having an upper and a lower arm connected by a bend, the lower arm having a terminal upward projection forming, with the bend, a downwardly extending recess adapted to receive an adjacent link.
